UNITED STATES PATENT OFFICE.

EDWIN L. EDES, OF PLYMOUTH, MASSACHUSETTS.

DESIGN FOR A LAMP-FOUNT.

SPECIFICATION forming part of Design No. 22,819, dated October 3, 1893.

Application filed August 26, 1893. Serial No. 484,157. Term of patent 14 years.

To all whom it may concern:

Be it known that I, EDWIN L. EDES, a citizen of the United States, residing at Plymouth, in the county of Plymouth and State of Massachusetts, have invented and produced a new and original Design for a Lamp-Fount, of which the following is a specification, reference being had to the accompanying drawings, showing parts thereof.

10 Figure 1, is a front view and Fig. 2 is a back view of the upper portion of the said lamp-fount intended to hold the usual apparatus for the production of light, whether by oil, gas or electricity.

15 The leading features of my design consist in the shape and configuration of a lamp-

fount representing a helmet of the Pilgrim type, and the ornamentation imprinted on said representation of the helmet in bas relief, on one side the well-known and celebrated 20 picture called "Landing of the Pilgrims" (see Fig. 1), and on the other side in like bas relief a representation of the ship "Mayflower" near the Plymouth coast sending its boats to shore. (See Fig. 2.) 25

What I claim is—

The design for a lamp-fount substantially as herein shown and described.

EDWIN L. EDES.
